F. V. Winter

Attorney

UNITED STATES PATENT OFFICE

MORRIS VICTORSOHN, OF BROOKLYN, NEW YORK

APPAREL APPARATUS

Application filed February 25, 1929. Serial No. 342,572.

This invention relates to apparel apparatus, and the improvements are directed to a novel form of support adapted to be mounted within a trunk or the like and associated therewith in a manner to permit its swinging removal therefrom to facilitate the hanging of garments thereon.

Heretofore it has been the practice to provide fixtures within a trunk or the like for supporting a plurality of hangers adapted to carry wearing apparel and similar articles, said hangers being in most instances removably attached to said fixtures and separable therefrom each time a garment is to be placed on a hanger for subsequent positioning in said trunk. In short, it has been necessary to remove a particular hanger from a trunk, place the garment thereon and replace said hanger.

It is therefore the primary object of the present invention to develop an improved hanger for garments, or the like, wherein it is unnecessary to actually remove the hanger from the trunk during the placement of the garment thereon, thus simplifying the packing or unpacking of a trunk.

Another object is to provide means for supporting a swingable hanger, said means being normally fixedly secured to a container, such as a trunk, for instance, and including cooperative means for maintaining the said hanger in an extended position or in a retracted location within the trunk.

Still another object of the invention resides in the provision of a rotatable hanger member adapted for removable engagement with certain supporting means, and the provision of a supplemental hanger fixedly borne by said supporting means and positioned in spaced relation to the former hanger member.

A still further object of the invention is to provide a device of the above-mentioned character, which is exceedingly compact in arrangement, easy to operate and comprising but a few simple parts.

With these objects in view, together with others which will appear as the description proceeds, the invention resides in the novel formation, combination and arrangement of parts, all as will be described more fully

hereinafter, illustrated in the drawings, and particularly pointed out in the claims.

In said drawings:

Figure 1 is a front elevation of my invention in retracted position within a trunk or other container.

Fig. 2 is a transverse sectional view taken on line 2—2 of Fig. 1; and

Fig. 3 is a view like unto Fig. 2, but showing the hanger in an extended position and protruding beyond the face of the body portion of a trunk.

Referring now in particular to the accompanying drawings, wherein like characters of reference denote similar parts throughout the several views, the numeral 5 designates generally a trunk, or similar container, having the usual side walls adapted to support my improved device, as shown in Fig. 1.

Upon inspection of the drawings it will be noted that I have provided a hanger 6, which substantially spans the space between the side walls of the trunk, and is adapted to receive garments or the like, said hanger being preferably rotatably mounted to permit adjustment of the said garments thereon as to overlapping heights, and to this end each of the extremities is provided with forwardly directed pintles 7 and 8 loosely mounted in arms 9 and 10 respectively. The intermediate portions of said arms are connected by a brace 11, which also serves as a hanger for garments, and as shown in Figs. 2 and 3, said brace 11 is provided with lateral extensions 12 and 13 which space the body portion of the former beyond the vertical plane of said hanger 6, as viewed in Fig. 2, the ends of said extensions being secured to said arms 9 and 10 as indicated at 14.

Each of the side walls of said trunk 5 is provided with a bracket 15, each having ears 16 and 17, suitably apertured to receive screws 18^a and 19 for rigidly attaching said brackets to said side walls. As shown in Fig. 1, the body portion of each of the brackets is spaced beyond the plane of the ears 16 and 17 for the reception of the lower ends of said arms 9 and 10, which are pivotally borne by said brackets, as indicated at 18, and since the lower ends of said arms are

spaced from the inner faces of said side walls, free pivotal movement of said arms and the hangers carried thereby is assured.

In Fig. 2, the normal position of the hangers 6 and 11, is shown. That is, the said hangers and the garments supported thereby are entirely within the trunk and in a packed or portable condition. However, when the time for unpacking arrives the door of the trunk is opened and the hanger 6 given a slight outward pull which rotates said arms 9 and 10 on their pivots 18, until the hanger 6 assumes the position shown in Fig. 3. It will be noted that the brace or hanger 11 is now spaced rearwardly of the first-named hanger 6, and the garments on either may be removed or replaced without interference from said hangers, or the garments carried thereby. The arms 9 and 10 are maintained in a substantially horizontal position in view of the engagement with the lower rear edge of said arms with the inner portion of the brackets above the ears 16, as will be quite apparent on inspection of Fig. 3. When it is desired to return the hangers within the trunk, the same are pushed upwardly to the position shown in Fig. 2, and the arms 9 and 10 are maintained in an erect position by the engagement of the detents 20 within the apertures 21 in said arms.

As shown in Fig. 1 the upper ends of said arms 9 and 10 are slightly offset, as shown at 22, and then directed upwardly and arranged curved in cross-section for the reception of pintles 7 and 8. This slight curvature adds rigidity to the structure and further provides a guide to facilitate the removal of hanger 6 when the arms are slightly spread apart, as is quite apparent.

From the foregoing it is manifest I have developed a device exceedingly simple in construction and admirably adapted for the uses noted hereinbefore. By adopting my hanger a relatively large quantity of garments may be supported in a trunk in pendent position and with the assurance that their positions will be maintained during the transporting of the trunk.

While the present is a disclosure of the preferred embodiment of the invention, it is to be understood that the same is not limited thereto, as various changes in the minor details of construction, proportion, and arrangement of parts may be resorted to without departing from the spirit of the invention as defined in the appended claims.

I claim:

1. In a device of the character described, brackets adapted to be secured to the sides of a container, arms pivotally borne by said brackets, a hanger carried by the upper ends of said arms and a supplemental hanger connecting the intermediate portions of said arms and positioned laterally of the vertical

plane of said first-named hanger in all positions of said hanger.

2. A device of the character described adapted to be secured to the sides of a container, a pair of arms pivotally borne by said container, a hanger carried by the upper ends of said arms and a supplemental hanger connecting the intermediate portions of said arms and positioned laterally of the vertical plane of said first-named hanger in all positions of said hanger.

In testimony whereof I affix my signature.
MORRIS VICTORSOHN.
